[57] CLAIM

The ornamental design for a modular duplexing module for an inkjet printing mechanism, substantially as shown and described.

DESCRIPTION

FIG. 1 is a perspective view of a modular duplexing module for an inkjet printing mechanism, in accordance with the present invention;

FIG. 2 is a top plan view thereof;

FIG. 3 is a front elevational view thereof;

FIG. 4 is a bottom plan view thereof;

FIG. 5 is a rear elevational view thereof;

FIG. 6 is a left side elevational view thereof; and,

FIG. 7 is a right side elevational view thereof.

The broken line showing of the duplexing mechanism, along with potential mechanical and electrical interconnections where the duplexing module is coupled to an inkjet printing mechanism, in FIGS. 1-4 and 6-7, is for illustrative purposes only and forms no part of the claimed design.
